[57] CLAIM

The ornamental design for work station, as shown and described.

DESCRIPTION

FIG. 1 is a front view of the work station of this invention in a first position;

FIG. 2 is a front view of the work station of this invention in a second position;

FIG. 3 is a front view of the work station of this invention in a third position;

FIG. 4 is a rear view of the work station of this invention in a first position;

FIG. 5 is a rear view of the work station of this invention in a second position;

FIG. 6 is a rear view of the work station of this invention in a third position;

FIG. 7 is a left side view of the work station of this invention in a first position;

FIG. 8 is a left side view of the work station of this invention in a second position;

FIG. 9 is a left side view of the work station of this invention in a third position;

FIG. 10 is a right side view of the work station of this invention in a first position;

FIG. 11 is a right side view of the work station of this invention in a second position;

FIG. 12 is a right side view of the work station of this invention in a third position;

FIG. 13 is a top plan view of the work station of this invention in a first position;

FIG. 14 is a top plan view of the work station of this invention in a second position;

FIG. 15 is a top plan view of the work station of this invention in a third position;

FIG. 16 is a front perspective view of the work station of this invention in a first position;

FIG. 17 is a front perspective view of the work station of this invention in a second position;

FIG. 18 is a front perspective view of the work station of this invention in a third position; and,

FIG. 19 is a front perspective view of the work station of this invention in a forth position.
